I claim the ornamental design for an audio enunciator housing, as shown and described.

DESCRIPTION

FIG. 1 is a first perspective view showing a first embodiment of my new design comprising an audio enunciator housing; FIG. 2 is a second perspective view of the audio enunciator housing of FIG. 1, rotated clockwise ninety degrees; FIG. 3 is a left side elevational view of the audio enunciator housing of FIG. 1; FIG. 4 is a right side elevational view of the audio enunciator housing of FIG. 1; FIG. 5 is a back elevational view of the audio enunciator housing of FIG. 1; FIG. 6 is a front elevational view of the audio enunciator housing of FIG. 1; FIG. 7 is a top plan view of the audio enunciator housing of FIG. 1; FIG. 8 is a bottom plan view of the audio enunciator housing of FIG. 1; FIG. 9 is a first perspective view showing a second embodiment of my new design comprising an audio enunciator housing; FIG. 10 is a second perspective view of the audio enunciator housing of FIG. 9, rotated clockwise ninety degrees; FIG. 11 is a left side elevational view of the audio enunciator housing of FIG. 9;

FIG. 12 is a right side elevational view of the audio enunciator housing of FIG. 9;

FIG. 13 is a back elevational view of the audio enunciator housing of FIG. 9;

FIG. 14 is a front elevational view of the audio enunciator housing of FIG. 9;

FIG. 15 is a top plan view of the audio enunciator housing of FIG. 9; and,

FIG. 16 is a bottom plan view of the audio enunciator housing of FIG. 9.

The broken line showing of portions of the audio enunciator housing is included for the purpose of illustrating portions of the “article” and forms no part of the claimed design. The dot-dash-dot lines form the boundaries of the claimed design.
